Attorney.

UNITED STATES PATENT OFFICE.

DANIEL FITZPATRICK, OF PROVIDENCE, RHODE ISLAND, ASSIGNOR OF
ONE - HALF TO PATRICK J. McCARTHY, OF PROVIDENCE, RHODE
ISLAND.

GAME APPARATUS.

No. 799,785.

Specification of Letters Patent.

Patented Sept. 19, 1905.

Application filed January 14, 1905. Serial No. 241,112.

To all whom it may concern:

Be it known that I, DANIEL FITZPATRICK, a citizen of the United States, residing at the city of Providence, in the county of Providence and State of Rhode Island, have invented certain new and useful Improvements in Game Apparatus, of which the following is a specification.

My invention relates to a "tenpin" game, which is played similar to that of the well-known regulation "bowling-alley" game, with the exception that my improved game is in miniature form and played with a cue-stick upon a table of special design and of the novel construction and combination of parts as hereinafter described and claimed.

In the accompanying sheet of drawings, Figure 1 represents a top plan view of my improved game-table with the balls and pins mounted thereon. Fig. 2 is a longitudinal view of the table, partly in section and partly in elevation, taken on line $\alpha\alpha$ of Fig. 1 and also indicating in dotted lines the relative position of the cue-stick for forcing the balls in contact with the pins. Fig. 3 is a transverse sectional view taken on line $\gamma\gamma$ of Fig. 2, showing the raised or playing surface of the table, with a channel or ball-raceway at either side thereof. Fig. 4 is a perspective view of a detachable shield for the rear end of the table. Fig. 5 represents the player's cue-stick. Fig. 6 is a perspective view of a quoit disk or ring as used in the game of "shuffleboard."

Like characters of reference indicate like parts in the several views of the drawings.

a designates the body portion of my improved game-table, which is mounted and secured upon suitable legs b . This table, which is made narrow and of any desired length, has a raised or ball-playing surface a' extending longitudinally of the table and terminating at one end with a pocket a^2 and at the other end with a pocket a^3 . At each side of the raised or playing surface a' of the table are channels or ball-raceways a^4 a^5 , whose bottom surfaces are located above the level of the pockets a^2 a^3 , as seen in Fig. 2. Surrounding the body portion of the table is a vertical flange a^6 , whose top edge is above the raised or playing surface a' of the table. The pocket a^2 is formed at the front end of the table for the reception of the balls c , and for the convenience of the player one corner

of the flange a^6 , at the front end of the table, is curved, as at a^7 , so that the balls which have been acted upon by the player and are made to return in the channel a^4 will be deflected in the arrow direction by this curved portion and enter said pocket a^2 . A piece of material made of felt d is secured transversely upon the playing-surface a' of the table and near to its ball-pocket a^2 for the purpose of holding a ball e in position thereon until acted upon by the player. The opposite or rear portion of the playing-surface a' is marked with a series of ten spots, as at points a^8 a^9 , and arranged in the same regulation order as on the floor of a bowling-alley for the purpose of placing a like number of pins e in their proper position thereon.

f designates the player's cue-stick, which is constructed similar to the cue-stick used in the well-known "pool" or "billiard" games.

To make a "shot," the player first rests the cue upon the front end flange a^6 of the table in the position indicated by dotted lines in Fig. 2. Thence with a sliding movement he strikes the tip end f' of the cue against the ball, which has been placed on the felt material d , and this blow causes the ball to roll upon the surface a' and eventually knock over one or more of the pins e into the rear pocket a^3 of the table.

To prevent the balls or pins from flying off the table after a strike has been made, I provide a shield g , constructed as shown in Fig. 4, comprising three walls g' g' and g^2 , which are secured by suitable means to hold together in a rigid position. The side walls g' have their bottom edges arranged to rest upon the top edges of the side flanges a^6 of the table, while the rear wall g^2 of the shield extends from the top of the walls g' to the bottom of the pocket a^3 , and this shield has two upright strips h h , each secured upon the outer surface of the side walls g' of the table and adapted to enter through hasps i i , which are secured to the side walls thereof in the manner shown in Fig. 1. This shield g not only serves to prevent the balls and pins from leaving the table when struck, but being detachable allows a player at each end of the table and each player to operate with a quoit or ring j (see Fig. 6) in sliding the same upon the playing-surface a' of the table to the line-marks k k , as in the well-known game of shuffleboard.

By my construction and arrangement of parts I form a very fascinating game, which may be played for a considerable length of time without much body exertion when compared to that required in a bowling game.

What I claim, and desire to secure by Letters Patent, is—

In a game apparatus, a table having a playing-surface of less length and width than the surface of the table, the table being formed with a pocket at each end of said surface and with a ball-channel at each side thereof communicating terminally with the pockets, said

pockets being on a plane below the ball-channels, and one of said channels being rounded adjacent to the pockets to direct the balls in the said pockets, and a shield adapted for removable connection with one end of the table, whereby said table is adapted for a plurality of games.

In testimony whereof I affix my signature in the presence of two witnesses.

DANIEL FITZPATRICK.
